TIRE

Aristides Makris, New Canaan, Conn., assignor to The
B. F. Goodrich Company, New York, N.Y., a corpora-
tion of New York

Filed June 14, 1968, Ser. No. 12,374

Term of patent 14 years

Int. Cl. D12—14

U.S. Cl. D90—20

FIG. 1

FIG. 2

FIG. 3

FIG. 1 is a perspective view of a tire showing the new design, it being understood that the opposite side of the tire is substantially like the the side shown;

FIG. 2 is a fragmentary transverse sectional view taken on the line 2—2 of FIG. 1; and

FIG. 3 is a fragmentary transverse sectional view taken on the line 3—3 of FIG. 1.

The novel features of the design reside in the portions shown in full lines.

I claim:

The ornamental design for a tire, substantially as shown and described.
